UNITED STATES PATENT OFFICE.

DAVID L. LINDQUIST, OF YONKERS, NEW YORK.

ELECTROMAGNET.

No. 892,065.

Specification of Letters Patent.

Patented June 30, 1908.

Application filed June 14, 1905. Serial No. 265,260.

To all whom it may concern:

Be it known that I, DAVID L. LINDQUIST, of Yonkers, Westchester county, New York, have invented a new and useful Improvement 5 in Electromagnets, of which the following is a specification.

The invention relates to an electro-magnet to be operated by a varying or alternating current without chattering or similar noises 10 resulting by reason of vibrations of the armature due to current variations in its coil.

The principle of the invention resides in the mechanical equilibration of the armature 15 against the attraction of the magnet and the taking up of the vibrations thereof due to current variations by means of a suitably placed resilient body forming the abutment of said armature. It will be observed, therefore, 20 that I do not prevent the armature vibrations by any construction of the magnet coil itself and thus avoid chattering; but on the contrary I permit them. I stop their effect upon contacts or any other rigid members 25 controlled by the armature by stopping them out, through the mechanical balancing of the armature against the magnet pull and their absorption by the interposed resilient abutment.

30 The accompanying drawing is an elevation of my improved varying current magnet.

The core B carries on one arm the electro-magnet coil A and to its other arm is pivoted the armature C. Said coil is supported in 35 any suitable way upon the back plate D, and projecting from said plate is a fixed arm E supporting the rods F. The armature C carries a rod G upon which is mounted a freely sliding plate H. Between said plate 40 H and a flanged sleeve I of insulating material, is interposed a helical spring J, which normally sets the plate H outward against its retaining pin K. The plate H and rods F form circuit terminals, and when 45 in contact establish circuit from the conductor to conductor, said conductors being connected respectively to rod G and arm E. The electro magnet coil is connected in circuit with a source of varying current that 50 may be derived from an alternating current

generator as symbolically indicated at L. The spring J is to be so constructed as mechanically to equilibrate the armature against the pull of the electro magnet, and so to form the abutment for said armature. 55 Hence when the armature is attracted to close circuit at the terminals H, F, no solid part of it meets any solid or fixed part of the apparatus against which it can chatter. After contact has been established at the 60 terminals, and the armature has become equilibrated, the spring will then still further operate to take up such vibrations of the armature as may be caused by current variations in the coil B, and in this way said 65 vibrations are stopped from reaching the terminals in contact and hence from causing intermittent separations and consequent chattering of said terminals. When the armature is in magnetic circuit with the 70 magnet core, as is here shown, the device becomes more sensitive and therefore this construction is preferable.

I claim:

1. A source of alternating current, an 75 electro magnet coil energized thereby, an armature therefor and a resilient abutment for said armature constructed to absorb the vibrations thereof due to current alternations in said coil.

2. A source of varying current, an electro magnet coil, an armature, means for mechanically equilibrating the attraction of said magnet upon said armature and for taking up the vibrations of said armature due to 85 current variations in said coil.

3. A source of varying current, an electro magnet coil, an armature, and a spring for equilibrating the attraction of said magnet upon said armature and for taking up the 90 vibrations of said armature due to current variations in said coil.

In testimony whereof I have signed my name to this specification in the presence of two subscribing witnesses.

DAVID L. LINDQUIST.
